UNITED STATES PATENT OFFICE.

HARRY C. BURKE AND AUGUST A. FRIBERG, OF LOS ANGELES, CALIFORNIA, AS
SIGNORS OF ONE-THIRD TO S. D. MURDOCK, OF LOS ANGELES, CALIFORNIA.

BILLIARD TABLE.

Application filed December 1, 1926. Serial No. 151,944.

This invention relates to devices used on billiards, pool-tables, and the like for controlling movements of balls.

One of the objects of this invention is to provide a ball control and collecting mechanism on so-called snooker-pool and English billiards.

Another object is to provide a controllable ball-return for billiard-tables.

Another object is to provide a ball-control for individually and collectively releasing the balls.

Other objects will appear from the following description and appended claims as well as from the accompanying drawing, in which—

Fig. 1 is a perspective illustration of a plain billiard-table with pockets into which balls are dropping as different games are played on the table with a ball-return below the table.

Fig. 2 is a fragmentary cross-section through one of the pockets approximately on line 2—2 of Fig. 1, illustrating a simple ball stop between the pocket and the return-channels.

Fig. 3 is a cross section through the pocket on line 3—3 of Fig. 2.

Fig. 4 is a diagrammatic illustration of a simple arrangement of several individual stops with means for universal or collective operation of the several stops in unison.

Fig. 5 is a fragmentary horizontal section through a pocket and adjoining return-channel with a ball-control of a slightly modified form.

Though there are many games played on billiard-tables, we only refer to some of the best-known games, such as snooker-pool and plain English billiard, in which the balls are frequently taken back from the pockets to be played over and over again on the table after having been dropped into the pockets during the course of the games.

In snooker-pool especially it happens frequently that so many of the red balls are discharged into one and the same pocket, that it becomes necessary for one of the players or attendants to remove some of the balls to one of the still empty pockets to allow a continuation of the game.

In this particular game quite a few red balls are discharged one after another until the game is finished, while balls of the other colors are, as a rule, wanted on the table

until all red balls have been played, though such otherwise colored balls are also repeatedly used in the game, so that they too drop into the pockets.

It stands to reason that any billiard in which the pockets are in free communication with any plain ball-return can not satisfactorily be used to play this game of snooker-pool, since the balls of the different colors would naturally enter the return system as soon as they are played into the pockets, while they should come back on the table for further use in the game.

To allow the use of a ball return system in connection with the pockets in a snooker-pool, we have therefore provided stop and release mechanisms, by which any number of balls can be held in the pocket preparatory to the release through the return-channels until certain of the balls, that are to be used for a continuation of the game, have been removed from the pocket, so that only such balls, that are not further desired in the game, can be released into the return-channel system for collection.

If, for instance, all the red balls shall be played first in a game and balls of other colors are to be repeatedly used in the game, such of the balls that have been discharged into the different pockets and that are to be used for further playing in the game are simply removed from a pocket and placed back on the table, while all the red balls are left in the pockets and are released directly after the other balls have been removed, or these red balls are released into the return channel system whenever it appears desirable or expedient during the game, or whenever any of the pockets become overfilled.

A simple form for holding or stopping several balls in the pocket before they are allowed to enter the return-channel system is illustrated in Figs. 2 and 3.

Any ball played on the table after being properly played to enter and pass the opening 7 drops into the pocket 8. This pocket is preferably made large enough to hold several balls to facilitate a playing of certain games, in which several balls may be discharged by the same player, after which some of the balls may have to be replaced on the table, as in the above referred-to snooker-pool. For holding several balls in any of the pockets preparatory to being

released into the return-channel 9, the stop 10 is removably disposed in the passage from the pocket 8 to the channel 9, as illustrated in Figs. 2 and 3. In this simple form, the 5 stop is turnably mounted on the shaft 11 and is provided with a handle portion 12 by which the shaft can be turned against the tension of the spring 13, so as to withdraw the stop-end 10 from the passage whenever the accumulated or collected balls in 10 the pocket are to be discharged into the channel 9.

Each pocket is preferably provided with such a stop for individually controlling the 15 pocket.

On the other hand, these individual stops and controls are provided with an actuating member 14 in form of a pin or similar abutment to allow an actuating of all stops 20 in unison, or collectively.

For collectively operating several stops of the whole billiard table, the bars 15 are provided with pins or abutments 16 by which the pins or abutments 14 of the individual 25 stops can be actuated, while still allowing an individual actuating of the stops by the handle-member 12. The joint operation of the several stops is made possible in a similar manner through the abutments 14-16 by a 30 pulling or moving of the bars 15 in the direction of the arrows 17, so as to turn the shafts with the stop-ends 10 jointly instead of individually as has been described above with reference to the handle-member 12 35 against the tension of the springs 13. Bell-crank 18 and connecting-rods 19 connect the two rods 15 to a common handle-lever, by which the whole mechanism can be actuated in unison for collectively discharging or re- 40 leasing balls from the several pockets of the whole billiard table. This main handle 20 together with the connecting rods 19 and the rods 15 are held in an inoperative position by a common spring 21, so that any of the individual 45 stops may be operated without affecting any of the stops in the other pockets, or without affecting the mechanism as a whole.

The slightly modified form illustrated in Fig. 5 is designed to be imbedded or incased 50 in the frame work of a billiard table, having a straight lever 22 pivotally mounted at 23 and connected at one end to the stop bar 24, disposed for horizontal movements across the path into the return-channel 9_a from the pocket 8_a. The bar 15_a is in this case also 55 provided with a pin 16 to abut against the protruding handle-portion 25 of the lever 22.

Any balls released from the pockets in the manner set forth above, after being dis- 60 charged through the return-channels 9, collect at one side of the billiard, as at the point indicated at 26, from which they may be taken after the game is finished to be replaced on the table.

65 In the snooker-pool game, all red balls

may in this manner be discharged into the collecting receptacle at 26, before the balls of other colors enter the return-channel system, and the red balls may therefore easily be collected first and unmixed of other balls 70 taken from the return system to be replaced on the table in one group ready for the next game. The balls of other colors having been played later to follow the red ball into the return system, may then be replaced in a 75 proper or desired order on the table after being also collected unmixed in one group.

From the above it will be understood that we do not make claim to any particular return system, and that the stop or release 80 mechanisms may be varied to suit different conditions of billiard tables within the scope of the appended claims.

Having thus described our invention, we 85 claim:

1. In a billiard table in combination with a ball return system under the table top and pockets in the table top, a ball control including stops with means for individually and other means for collectively operating 90 said stops for holding and releasing balls in the several pockets to be released into said return system.

2. In a billiard table having a rim around the table top with pockets extending through 95 the rim from above the table top to a point below the table top, a ball collecting system below the table top in communication with said pockets, and a ball control mechanism including stops with means for individually 100 and other means for collectively operating said stops for holding and releasing balls in the several pockets.

3. In a billiard table in combination with a ball return system under the table top and pockets in communication with the return system, a movable stop adapted to interrupt the communication between each of the pockets and the return system, means for individually operating the stops, and other 110 means for collectively operating all stops simultaneously.

4. In a billiard table in combination with a ball return system and pockets in communication with the return system having 115 an aperture at a point near each of the pockets, a stop swingably mounted on the outside of each of the pockets having an extension end adapted to move through said aperture to interrupt the communication between said pockets and said return system, means for individually manipulating the stops, and other means for collectively manipulating the several stops simultaneously. 120

In testimony that we claim the foregoing 125 as our invention we have signed our names.

HARRY C. BURKE.
AUGUST A. FRIBERG.
